CLAIM

We claim the ornamental design for a food heating pellet, as shown and described.

DESCRIPTION

FIG. 1 is a perspective top view of the food heating pellet looking from the front left side.

FIG. 2 is a bottom perspective view looking from the front left side.

FIG. 3 is a front elevation view.

FIG. 4 is a left side elevation view.

FIG. 5 is a top plan view.

FIG. 6 is a right side elevation view.

FIG. 7 is a back elevation view; and,

FIG. 8 is a bottom plan view of the food heating pellet.
